Primary Examiner — T Chase Nelson*Assistant Examiner* — Kelly L Gross(74) *Attorney, Agent, or Firm* — Chun-Ming Shih; HDLS IPR SERVICES(57) **CLAIM**

The ornamental design for an X-ray security machine as shown and described.

DESCRIPTION

FIG. 1 is a perspective view of an X-ray security machine showing my new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines in the drawings illustrate portions of the X-ray security machine that form no part of the claimed design.
